UNITED STATES PATENT OFFICE.

JULIUS W. KNOPP, OF TOLEDO, OHIO.

ATTACHMENT FOR WAGONS FOR LOADING OR UNLOADING STONE.

SPECIFICATION forming part of Letters Patent No. 623,676, dated April 25, 1899.

Application filed April 4, 1898. Serial No. 676,371. (No model.)

To all whom it may concern:

Be it known that I, JULIUS W. KNOPP, of Toledo, county of Lucas, and State of Ohio, have invented certain new and useful Improvements in Portable Attachments for Wagons for Loading or Unloading Stone; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to a portable attachment to wagons for loading and unloading stone, and has for its object to provide a mechanism transportable with the wagon, whereby when either at the source of supply or delivery the mechanism may be erected and operated to either load upon the wagon or deliver the load from the wagon to the desired place of deposit.

Figure 1 is a side elevation showing the truss-winch and tackle. Fig. 2 is a top plan view. Fig. 3 is a rear end elevation. Fig. 4 is a detail view showing the carrier-beam and traveler. Fig. 5 is a view in side elevation of a section of carrier-beam with the traveler thereon. Fig. 6 is a detail view of the block and link which supports the traveler-beam.

I have constructed a wagon with my improved attachment in which the divergent sills are of I-beam iron, and suspend the sills by stirrups 2, although I may employ the ordinary wagon constructed for transporting stone, and upon the bed of the wagon I erect a truss 3, preferably of T-beam iron, the side rail of the truss converging to a center, as at 4, and at this point I journal a sheave 5, preferably of three sections, and intermediate the length of one of the divergent sections of truss, as at 6, I journal a winch 7, over which is reeved a rope or cable 8, and mount upon the shaft of the winch a drum 9, having perforations 10 to receive the end of a bar 11, by which to revolve the winch. The rope or cable 8 is also reeved over the sheave 5, and one or more strands are reeved over a pulley 12 of a block 13, having a link 14, in which rests one end of a traveler-beam 15, by which means when the drum 9 is revolved the traveler-beam is either raised or lowered,

as desired. The traveler-beam 15 is supported at the opposite end upon a standard 16, the base of which may rest upon the curbing 17, and is formed with notches or rests 18, into which a link 19, secured to the traveler-beam, may rest.

I mount upon the traveler-beam 15 a block 20, having a roller 21, which rests upon the beam, and in the frame 22 of the block there is passed a rope or cable 23, which acts as a sling to embrace the load 24 of stone either by being secured to metal hooks 25 or otherwise.

It will be evident that I may strengthen the framework by truss-irons, as shown at 26 in Fig. 3, or in any preferred manner.

In the employment of the skeleton metal bed of I-beams 1 I may provide for a resilient movement to compensate for unevenness of the road by interposing a spring 27 upon the front axle 28, and to lend rigidity I may secure a brace-iron 29 upon the truss and allow the opposite end 30 to embrace the standard 75 65 31, upon which the spring 27 is coiled.

In operation the wagon is driven to the source of supply of the stone, the standard 16 is erected, and the link 19 adjusted in one of the notches 18 to incline the beam 15 toward the wagon, the pulley 12 being also lowered by manipulating the winch. The sling is now secured around the stone and the beam 15 slightly raised by elevating the pulley 12 by the manipulation of the winch, whereby 85 the stone is lifted from the ground and caused to travel by gravity to coincide with the bed of the wagon, and the stone is rested thereon by lowering the beam by means of the pulley 12, after which operation the slings are detached from around the stone, the beam and standard loaded upon the wagon, and driven to a point of delivery, where the operation is reversed. By this means one man can accomplish the work hitherto requiring three 90 or four.

I prefer to drill holes along the top portion of the beam 15, into which may be inserted stop-pins 32 to limit the movement of the sling and load.

It will be understood that the drum 9 and shaft are controlled by the usual ratchet and pawl to control the winding up of the load and with a friction-brake to allow a control-

lable descent of the same, these provisions being of the usual order.

What I claim is—

In a wagon and portable attachment for loading and unloading stone, a bed having a truss mounted thereon comprising two members converging from both ends toward the apex and having a pulley or tackle block secured thereon by a flexible medium, and means for controlling the medium consisting of a winch secured to the truss members, a traveler-beam supported by the pulley-block

at one end, the other end being adjustably supported by a standard having a serrated edge, and a traveler upon the beam adapted to travel in the direction of inclination of the beam.

In testimony that I claim the foregoing as my own I hereby affix my signature in presence of two witnesses.

JULIUS W. KNOPP.
